UNITED STATES PATENT OFFICE

JOHN MILLER, JR., OF BELOIT, WISCONSIN, ASSIGNOR TO CHARLES H. BESLY & COMPANY, OF CHICAGO, ILLINOIS, A CORPORATION OF ILLINOIS.

DISK GRINDER.

Application filed January 16, 1920. Serial No. 251,759.

To all whom it may concern:

Be it known that I, JOHN MILLER, Jr., a citizen of the United States, and a resident of Beloit, in the county of Rock and State 5 of Wisconsin, have invented certain new and useful Improvements in Disk Grinders, of which the following is a specification.

This invention relates to improvements in disk grinders and more particularly to a 10 novel construction for a disk grinder of the horizontal type embodying certain improved features pertaining to those parts designed to accomplish the removal of the dust and particles of material resulting from the 15 grinding operation.

The object of the invention is to provide an improved structure calculated to overcome the disadvantages of the construction now commonly employed, thereby producing 20 a more efficient and desirable machine. A disk grinder of the horizontal type has been heretofore constructed to include what is known as a dust ring, namely, a hollow ring made up of one or more hollow sections of 25 cast metal which surrounds the periphery of the disk, said sections being provided with a series of apertures or slots arranged along the side thereof adjacent the disk. The passages and slots of the rings were produced 30 by the use of cores, and as a result the passages were rough, uneven, and varying in cross-sectional area, and the slots necessarily not of uniform width and distribution. The use of exhaust rings was found to be 35 objectionable in that it was difficult to maintain a uniform suction at all points of the periphery of the disk and hence there was imperfect removal of the dust.

By constructing a machine in the manner hereinafter pointed out and as embodied in the invention, it is possible to not only eliminate the use of a cast metal exhaust ring but to completely overcome the imperfections of its use. The features embodied in 45 the invention are hereinafter fully set forth and illustrated in the accompanying drawings, in which—

Fig. 1 is a view in side elevation of a 50 disk grinder constructed in accordance with the invention,

Fig. 2 is a top plan view of the grinder, and

Fig. 3 is a detail view in cross section of 55 the grinder showing the construction of the exhaust chamber and slot.

The drawings illustrate a disk grinder of the horizontal type ordinarily employed in the finishing of small castings and the like, the same comprising a cylindric-shaped base or pedestal 1 which preferably rests upon a 60 base plate 2. The pedestal 1 is a hollow casting within which is enclosed a vertical spindle 3 mounted in bearings at 4 and 5, the spindle extending upwardly through the upper wall 6 of the pedestal in which is 65 mounted the spindle bearing 5. Upon the upper end of the spindle 3 is mounted the grinding disk 7, the same comprising a flat circular metal disk to the upper face of which is applied a sheet or coating of 70 abrasive material.

The spindle and disk are rotated or driven by suitable mechanism consisting of a horizontal drive shaft 8 which extends into the interior of the pedestal and has driving connection with the spindle through the medium of miter gears 9 and 10 fixed to the shaft and spindle respectively. The drive shaft 8 is supported adjacent its outer end in a bearing 11 and at its inner end in a bearing 12 supported by the pedestal 1. On the shaft 8 are mounted loose and fixed pulleys 13 and 14 respectively, adapted to carry a belt, there being employed the usual form of belt shifter 15 and lever 16.

Referring more in detail to the structure of the grinder and those parts to which my invention relates there is mounted upon the upper end of the pedestal a body member 17 having the shape of a shallow inverted 90 frusto-conical shell interposed between the pedestal 1 and the disk 7. This body member is of cast metal having a base or bottom wall 18 resting on and secured to the pedestal 1 and outwardly and upwardly inclined or tapered walls 19 terminating in an annular flange 20 surrounding the periphery of the disk 7 and lying substantially in the plane of said disk, or, as clearly shown in Fig. 3, the upper face of the flange is slightly 100 below the plane of the under face of said disk. Mounted upon the flange 20 of the body member is a ring 21 of L-section which is secured in place by means of bolts 22, said ring projecting above the surface of the disk and acting as a surrounding wall to maintain the articles or parts upon the revolving disk. As a preferable construction the inner annular surface of the flange 20 of the body member is finished or machined to provide a 110

beveled surface as at 23, Fig. 3, said beveled surface being spaced a short distance from the lower edge of the periphery of the disk 7. Obviously this beveled surface extends entirely around the periphery of the disk and forms a uniform slot between the periphery of the disk and the body member 19. Not only is the beveled surface 23 machined or finished but also the upper surface of the flange 20 and the inner surface of the ring. Needless to say the disk itself is finished and accurately machined at its periphery. Thus it is obvious that there is provided a slot extending completely around the disk, said slot being formed between two accurately machined or finished surfaces of the body and the disk. The slot communicates with the exhaust chamber formed between the under surface of the disk 7, the portion of the wall 19 below the disk and a vertical annular partition wall 19^a formed integral with the body 17 adjacent the base 18. The dust is drawn through the slot as it is impelled outwardly to the edge of the disk by centrifugal action or by the suction produced within the chamber or interior of the body by means of an exhausting apparatus, preferably in the form of a blower 24 mounted adjacent to the pedestal and driven by a belt 25 from the main drive shaft 8, and a pulley 26 carried by said shaft. From the blower 25 there extends an exhaust pipe 27 which communicates with the interior of the chamber at two diametrically disposed outlet connections 28 and 29, the exhaust pipe being curved in order to hug closely the pedestal 1, and being gradually reduced in diameter as it approaches the more distant exhaust outlet 29. The operation of the blower obviously exhausts the air from the interior of the chamber, carrying with it the dust that is drawn through the slot.

Among the features of the construction employed there may be pointed out the location of the dust exhaust chamber and the manner in which it is formed, it being observed that the same is located completely beneath the disk and hence removed from those portions of the machine that should be freely accessible in the operation thereof. It is to be observed that in forming the chamber a part of the machine is utilized which otherwise is practically wasted, by providing a body member immediately be-

neath the disk, which member is a simple form of casting in which no cored passages or openings are necessary. A further feature to be noted is the employment of the disk itself as a wall or top closure of the chamber whereby the parts forming the chamber are reduced to a minimum, all of which aids in the production of a lighter, simpler and more efficient machine.

In like manner the formation of the slot between the accurately machined surfaces of the body member and the disk itself promotes the efficiency of the machine by providing a continuous, uniform slot for the removal of the dust without the presence of added parts designed for this particular purpose. By this arrangement not only is the weight of the machine and its manufacture simplified but the efficiency of the exhausting apparatus materially increased by the production of an accurately formed slot between two finished surfaces which is obviously impossible to produce in a cast or cored dust removing member as for instance, an exhaust ring.

These features of construction unite to produce a more efficient machine of simpler and less expensive construction, in the production of labor-saving machinery.

Although I have described and illustrated a definite embodiment of the invention, the details thereof may obviously be modified without departing from the spirit of the invention, and therefore I do not wish to be limited except in so far as the invention is specifically set forth in the appended claim.

I claim as my invention:

In a grinding machine, the combination of a pedestal including a flaring wall portion and a vertical partition wall, a spindle journaled in said pedestal, having a disk mounted at the upper end thereof, said flaring wall portion having a finished marginal surface spaced below the under side of said disk, and forming therewith a slot, communicating with an exhaust chamber formed between said disk, flaring wall portion and vertical partition wall, and a dust ring secured to the marginal portion of said flared wall portion and spaced radially from the edge of said disk.

In witness whereof, I hereunto subscribe my name this 10th day of Jan., A. D., 1920.

JOHN MIELLER, JR.
